United States Patent Office

Des. 220,586
Patented Apr. 27, 1971

220,586

CALCULATING MACHINE

James H. Frakes, Jr., Manlius, and Chester J. Abend,
Camillus, N.Y., assignors to SCM Corporation, New
York, N.Y.

Filed Sept. 24, 1969, Ser. No. 19,289

Term of patent 14 years

Int. Cl. D18—01

U.S. Cl. D64—11

Fig. 1

Fig. 2

FIG. 4

FIG. 6

FIG. 3

FIG. 5

FIG. 1 is a front perspective view of a calculating machine showing our new design;

FIG. 2 is a top plan view thereof;

FIG. 3 is a front elevational view thereof;

FIG. 4 is a right hand elevational view thereof;

FIG. 5 is a rear elevational view thereof; and

FIG. 6 is a left hand elevational view thereof.

We claim:

The ornamental design for a calculating machine, substantially as shown.
